UNITED STATES PATENT OFFICE

2,496,604

MOLDING MACHINE

Andrew Scott, Chicago, and James B. Amstutz,
Oak Park, Ill., assignors to Crane Co., Chicago,
Ill., a corporation of Illinois

Application April 4, 1946, Serial No. 659,612

3 Claims. (Cl. 22—30)

1

This invention relates to molding machines and has for an object the provision of a molding machine which operates automatically through a complete molding cycle to compress the sand in a flask, actuate a rapper, lower the pattern plate to strip the mold, and then lower the stripper plate to its first position to complete the cycle of operation.

It is a further object of this invention to provide a molding machine embodying means for applying a predetermined uniform pressure in compressing the sand to form each mold to insure the formation of molds having a substantially equal density. It is further contemplated that the molding pressure exerted in compressing the sand may be readily adjusted to suit the operator in order to obtain the proper predetermined density in molds of different sizes, shapes, etc.

Another object of this invention is to reduce to a minimum the manual effort required of the operator in forming molds on a molding machine of this type.

It is another object of this invention to provide adjustable timing means for determining the commencement and duration of the various steps throughout the complete cycle of automatic molding operation.

This invention further contemplates the provision of a molding machine which is simple in construction, reliable in operation, and which will not readily get out of order due to wear, breakage, or the deleterious action of sand against bearing surfaces.

Another object of this invention is to provide an improved means for operating the stripper frame to improve the quality of the mold and the products to be formed therein.

This invention embodies other novel features, details of construction, and arrangement of parts which are hereinafter set forth in the specification and claims and illustrated in the accompanying drawings, forming part thereof, wherein:

Fig. 1 is a front elevational view of a molding machine embodying features of this invention.

Fig. 2 is an enlarged view taken along the line 2—2 of Fig. 1.

Fig. 3 is a sectional view taken along the line 3—3 of Fig. 2.

Fig. 4 is a diagrammatic view showing the air control circuit employed for operating the molding machine.

Fig. 5 is an enlarged sectional view of one of the timer valves.

Referring now to the drawings (Fig. 3) for a better understanding of this invention, the im-

proved molding machine is shown comprising a base 11 having a piston supporting member 12 secured thereto by means of screws 13. A piston 14 is securely mounted upon the upper end of the member 12, and is provided with suitable sealing rings 17 for leakproof, sliding engagement with the wall of a lift cylinder 18. A guide plate 19 is bolted to the lower end of the lift cylinder 18 for reciprocable engagement with the piston supporting member 12, and is provided with a wiping seal 21 to remove any dirt or sand from the member 12 and to prevent the infiltration of sand and dirt into the cylinder. Guide shoes 22 are secured to opposite sides of the cylinder 18 for sliding engagement with guide posts 23 to prevent rotational movement of the cylinder. A breather pipe 20 leads from the cylinder 18 to an air filter (not shown).

A plate pattern holder 26 is securely mounted upon the lift cylinder 18 and is formed with a suitable recess 27 to receive a plate pattern 28. A stripper frame 29 encloses the upper end of the holder 26 and is guided for vertical movement by means of a pair of guide pins 31 (see broken away portion of Fig. 3) adjustably mounted on diagonal corners of the holder for engagement in guide bearings 32 secured to the frame. The guide pins 31 also engage hardened stop buttons 33 when the stripper frame is in its lower position to insure that the upper surface 34 of the stripper frame is flush with or slightly lower than the upper surface 36 of the holder. Hardened wear bushings 37 are provided in the guide bearings 32, and seal washers 38 are provided to protect the bearing surfaces from dirt and sand. A pair of stop pins 39 (Fig. 2) are adjustably secured on the other two corners of the holder to act with the guide pins 31 to position the holder in its lower position.

A pair of cylinders 41 are secured to the underside of the stripper frame 29 to receive pistons 42 having shaft portions 43 projecting downwardly through cover plates 44 for engagement with adjustable stop buttons 46. The stop buttons are threaded into the upper ends of the guide posts 23 and locked against displacement by locknuts 47. Annular seals 48 are provided in the cover plates 44 for protection against the entrance of sand in cylinder 41. A protective guard 10 is provided around the cylinders as indicated.

Four flask aligning pins 49 are provided to project upwardly from the upper surface 36 of the holder 26 to engage in apertures (not shown) provided in a flask fragmentarily referred to at 51. A rapper 52 is mounted on the holder below

the plate pattern. The plate pattern is heated by means of an electric or gas unit (not shown) mounted inside the holder 26. The usual squeeze plate 50 is supported on upright members 55 secured to the base 11.

Fig. 4 illustrates diagrammatically the combined valve and piping means employed for controlling the operation of the molding machine. Air under pressure flows through an inlet pipe 56 from a source of pressure to a three-way control valve 57 which is opened to the air inlet pipe 56 by operating the handle 58 and is closed to the air inlet and opened to exhaust to the atmosphere by means of a spring (not shown), and thence from the valve 57 through a conduit 59 to the interior of the lift cylinder 18 above the piston 14. The inlet pipe 56 also leads through a conduit 61 to the inlet ends of a pair of similar Schrader three-way adjustable timer valves 62 and 63.

Each timer valve comprises a body 64 having an inlet passage 66 and an outlet passage 67. A valve disc 68 having two closure seats 69 and 71 is reciprocably mounted in the valve body and normally held in its upper position by means of a helical compression spring 72 for closing the inlet passage 66 by means of the closure seat 69. A piston 73 having a piston stem 74 is mounted in a cylinder 76 for actuating the valve disc 68. An exhaust passage 70 is provided in the lower end of the stem 74 and leads from the outlet passage 67 to the atmosphere under control of the closure seat 71. The piston is normally held in its upper position by means of a compression spring 77 and with the lower end of the stem 74 out of engagement with the closure seat 71. An air bleeder passage 75 leads from the interior of the cylinder 76 to the atmosphere under control of an air control screw 78.

A conduit 79 leads from the conduit 59 to a spring actuated adjustable pressure relief valve 81 to open upon predetermined pressure, and a conduit 82 leads from the valve 81 to the upper ends of the cylinders 76 of the timer valves 62 and 63. A conduit 83 leads from the outlet passage 67 of the timer valve 62 to the stripper cylinders 41, and a conduit 84 leads from the outlet passage of the timer valve 63 to the rapper 52.

In the operation of the molding machine thus described, a flask 51 is positioned on the surface 36 of the pattern plate holder 26 and located by means of the pins 49, as shown in Fig. 3. After filling the flask with sand, the lever 58 of the control valve 57 is actuated by the operator to permit air under pressure to flow through the conduit 59 to the lift cylinder 18 to cause same to move vertically. As the lift cylinder reaches its upper position, the sand is compressed within the flask by the squeeze plate 50 (Fig. 1) until the resultant rise in air pressure causes the pressure relief valve 81 to open and permit the passage of air to the cylinders 76 of the timer valves 62 and 63. The pistons 73 are then actuated to seat the valve 74 on the seat 71 and simultaneously to unseat the closure 68 from the seat 69 to permit air under pressure to pass from the conduit 61, through the inlet passages 66, outlet passages 67, and conduits 83 and 84 to the stripper cylinders 41 and rapper 52, respectively. Upon the operation of the rapper, the operator releases the handle 58 of the control valve 57 to permit same to shut off the supply of air to the lift cylinder 18 and relief valve 81, and at the same time permit the air within the cylinder 18 to return through the conduit 59 and exhaust to the atmosphere through the control valve.

During the downward movement of the cylinder 18, the pattern plate 28 is stripped from the mold by means of the pistons 42 having their shaft portions 43 engage the stop members 46 and thereby stop the downward movement of the stripper frame 29 and the flask supported thereon while the pattern plate holder 26 continues its downward movement to its initial starting position. While the stripper frame is in its stripping position, the flask is removed therefrom by the operator. During the downward travel of the cylinder 18, the compressed air within the timer valves 62 and 63 is being bled from their cylinders 76 through their bleeder passages 75 and as regulated by their respective flow control screws 78 to permit the springs 72 and 77 to act to move the closure seats to close the air inlet passages 66 and to open the exhaust passage 70. The timer valve 63 is regulated or timed to stop the operation of the rapper after the pattern plate is stripped from the mold, and the timer valve 62 acts to exhaust the air from the cylinders 41 after the mold has been removed from the stripper frame to permit the latter member to drop to its loading or starting position.

It is obvious to those skilled in the art that many changes in details may be made without departing from the scope or spirit of the invention.

Having thus described our invention what we claim is:

1. In combined valve and piping means for a molding machine or the like, fluid supply means and conduit therefor including a lift cylinder in communication with said fluid supply means, stripper cylinders and a rapper to be actuated by said fluid supply means, a multi-way control valve in said fluid supply conduit, the said control valve upon actuation being closed to the fluid supply and opened respectively to exhaust to atmosphere and to communicate with the interior of the said lift cylinder, a plurality of multi-way timer valves in communication with the said fluid supply, each of the said timer valves having a pair of closure seats, and having a piston portion for actuating one of the closure seats and an air bleeder passage from the said piston means, a pressure relief valve in communication with said lift cylinder and adjustable to open upon predetermined pressure, conduit means leading from the said relief valve to the piston portion of the said timer valves, conduit means from the outlet side of one of the timer valves communicating with the said stripper cylinders and conduit means from the outlet side of the other of said timer valves in communication with the rapper.

2. Valve and piping mechanism for actuating a molding machine or the like, a fluid supply and conduit therefor including a lift cylinder at the base of the machine in communication with said fluid supply, stripper cylinders and a rapper superposed above the said lift cylinder and actuated by fluid within the said supply conduit, a multi-way control valve being in said fluid supply conduit and predeterminedly closed to the fluid supply and opened to exhaust to atmosphere and communicating with the said lift cylinder, a plurality of multi-way timer valves in communication with the said fluid supply, the said timer valves each having a pair of closure seats and piston means for actuating one of the closure seats and an adjustable air bleeder passage from the said piston means, pressure responsive mean in communication with said lift

cylinder, the said lift cylinder exhausting through the said control valve, conduit means from the said pressure responsive means to the said timer valves, conduit means from one timer valve communicating with each of the stripper cylinders and conduit means from the other timer valve in communication with the rapper.

3. An actuating system comprising valves and fluid conduits for a molding machine or the like, the combination including a lift cylinder in communication with a fluid conduit, stripper cylinders and a rapper actuated by fluid within said fluid conduits, a three-way valve in one of said fluid conduits, the said latter valve upon actuation being closed to the fluid conduit and opened to exhaust to atmosphere and being connected with the interior of the said lift cylinder, a plurality of timer valves in communication with the said fluid supply, the said timer valves each having a pair of upper and lower closure seats and resiliently mounted piston means and stem for actuating the closure seats, the said piston means being normally maintained in its upper position and with the stem out of engagement with the lower closure seat, the said timer valves having air bleeder passages from above the said timer piston means, a pressure relief valve adjustable to open upon predetermined pressure in communication with said lift cylinder, conduit means from the said relief valve to the piston means of the said timer valves, conduit means from the outlet side of one of the timer valves communi-

cating with the said stripper cylinders and conduit means from the other of said timer valves in communication with the said rapper, one of said timer valves predeterminedly stopping the operation of the rapper, the other of said timer valves predeterminedly exhausting the fluid from the said stripper cylinders to enable the molding machine to return to its mold loading position.
